HINGED TABLET ARM CHAIR

Philip J. Hendrickson and Richard J. Resch, Green Bay,
Wis., assignors to Krueger Metal Products, Inc., Green
Bay, Wis.

Filed Jan. 27, 1972, Ser. No. 221,488

Term of patent 14 years

Int. Cl. D6—01

U.S. Cl. D6—42

FIG. 1 is a view in three-quarter rear perspective showing our improved design.

FIG. 2 is a view in front three-quarter perspective thereof.

FIG. 3 is a front elevational view thereof.

FIG. 4 is a plan view thereof.

FIG. 5 is a bottom three-quarter rear perspective thereof.

FIG. 6 is a side elevational view thereof.

FIG. 7 is a bottom plan view thereof.

FIG. 8 is a view on a reduced scale of section 8—8 of FIG. 2.

The characteristic feature of the design resides in the particular configuration of the double bar tablet support. We claim:

The ornamental design of a hinged tablet arm chair, as shown and described.
